5 Claims. (Cl. 242—78.8)

The present invention relates generally to metal strip processing equipment and more particularly to improved apparatus for opening the outer convolution and end of a coil of metal strip, such apparatus generally being known in the art as "coil peelers."

It will be understood that a substantial portion of the strip material produced in various steel plants is formed in coils to facilitate transportation from the point of manufacture or processing to the point of further processing. At the point at which such strip is to be further processed it is necessary to unwind the coil in order that it may be passed into and fed through machines of one kind or another for further working of the material. In utilizing prior art apparatus difficulty has been experienced in starting the outer end of the coil into such processing machines, especially if the strip is of any appreciable thickness, since the outer convolution of the coil is extremely hard to "break" from the coil proper for initial feeding into the machines.

This problem has been greatly accentuated by virtue of advances made in other arts whereby the speeds of strip processing lines have been increased in recent years and the time required to feed a new coil into the processing line has become more critical. This is particularly true where continuous process lines are employed, as in electro-plating of strip material, or the electric welding of tube formed from strip material, for example, since the time consumed in initially feeding a coil into the process line limits the speed of the line or dictates the use of large and costly strip storage facilities, such as looping rolls or loop pits. Although this problem has been recognized in the prior art and attempts have been made to provide suitable coil peelers, the need still exists for such apparatus which is operative to break the outer end of a strip of metal from a coil in a minimum of time and yet not interfere in any manner with the normal operation of the processing apparatus. It is accordingly the primary or ultimate object of the present invention to provide an improved coil peeler well adapted for use in freeing the outer end of a metal strip from a coil.

A further object of the invention is to provide a coil peeler wherein the same may be automatically retracted from engagement with the strip after the outer end of the coil has been loosened and fed into machines so that the operation of the processing line is not impaired in any manner.

Another object of the invention is to provide apparatus of the character described wherein the actual coil-engaging fingers or wedges are adjustable to engage coils of various outer diameters and shapes. As will be hereinafter more fully explained, the fingers or wedges are adapted for transverse sliding movement with respect to the pass line of the strip material and are rotatable or movable in a generally vertical direction with respect thereto. In connection with this object, it is an auxiliary object of the invention to provide means for moving and actuating the coil peeler in an improved manner.

Yet another object of the invention is to provide a coil

peeler which is adapted to be attached or mounted on and from a piece of equipment usually found at the head of a process line, such as a roller leveller, for example, whereby separate mounting means etc., are not needed or contemplated.

Another object of the invention is to provide a coil peeler which is characterized by its utmost simplicity in construction and operation. The construction is such that only a few and relatively simple parts are employed and 10 one operator can easily and swiftly separate the end from a coil of strip material in a minimum of time.

These objects, as well as other objects and advantages of the invention, will become more readily apparent upon further consideration of the following complete specification with reference to the accompanying drawing.

In the drawing:

Figure 1 is a side sectional view of the beginning of an illustrative processing line embodying a coil peeler constructed in accordance with the teachings of the present 20 invention;

Figure 2 is an enlarged plan view of a portion of the apparatus shown in Figure 1 showing specifically the roller leveller and the coil peeler mounted thereon;

Figure 3 is a front elevation of the apparatus depicted 25 in Figure 2;

Figure 4 is a side sectional view of the apparatus shown in Figure 3 taken along the section line IV—IV;

Figure 5 is a sectional view taken along the section line 30 V—V of Figure 4;

Figure 6 is an enlarged and fragmentary sectional view taken along the section line VI—VI of Figure 4; and

Figure 7 is a side view of the apparatus shown in Figure 6.

Referring now to the drawing, and initially to Figure 1 35 thereof, there is shown in somewhat schematic fashion the beginning portion of a continuous process line for working or forming metal strip that embodies a coil peeler constructed in accordance with the teachings of the present invention. Coils of metal strip, designated by the reference numeral 10, are placed on the far end of a conveyor 11, the bottom portion thereof being shown in broken lines, which is entrained about the sprockets 12 and supported by a suitable structural framework 13 above a concrete base 14. Suitable driving means, not shown, are provided for intermittently advancing the conveyor 11 40 whereby coils supported thereon are advanced toward an uncoiling station 15. The uncoiling station 15 includes a power driven uncoiler of conventional construction having movably mounted opposed and transversely spaced frusto-conical coil-engaging heads 16 adapted to be inserted in the opening or eye of the coil at the uncoiling station. It will be observed that only the forward edge of one coil-engaging head is shown in Figure 1 of the drawing. The co-pending patent application of Kenneth L. Bandy, Serial 50 No. 429,239, filed May 12, 1954, which has since matured into U.S. Patent No. 2,800,288 and is assigned to the assignee of the present invention, shows a preferred type of uncoiler although it will be understood that other types of uncoilers may be utilized.

Intermediate the transversely disposed coil-engaging 55 heads 16 of the uncoiler is a coil saddle 17 which is adapted to initially support a coil of strip material. The coil saddle 17 is vertically adjustable by means of a fluid cylinder 18 whereby the center opening or eye of the coil may be accurately aligned with the coil-engaging heads 16 irrespective of the outer diameter of the coil.

When a coil has been properly positioned by the saddle 17 and engaged by the uncoiler it is necessary to break or loosen the outer end of the strip from the coil so that this end may be fed into the various processing 60 apparatus. This is accomplished in the present instance by our improved coil peeler which is generally designated 70

by the reference numeral 19 and whose structure and operation will be hereinafter more fully described.

After the end of the coil is freed it is guided through a roller leveller 20 and to a shear 21 where the leading end of the strip is accurately cropped. From the shear 21 the strip end may proceed to a welding machine, not shown, where the sheared leading strip end is welded to the trailing end of another strip section to form a continuous length of metal strip. The strip may then be fed through any of a series of processing machines not shown, operative to work or process the strip in the manner desired. The arrangement shown in Figure 1 of the drawing may be the beginning of an electric weld pipe mill or an electro-plating line, for example. The direction of strip travel is shown by the arrow in the drawing.

Considering now the structure of the roller leveller 20 and the coil peeler 19 associated therewith, reference is made to Figures 2-4 of the drawing wherein there is shown a table-like support 24 which mounts the roller leveller 20 and coil peeler 19 above the base 14. The roller leveller comprises a housing 25 which is open to allow the passage of strip material therethrough and supports a set of lower working rolls 26 which are journaled at their opposite ends in said housing. A set of upper working rolls 27 have their ends journaled in vertically movable blocks 28, one set of blocks being provided for each of the upper working rolls, which are guided for vertical movement by slides, not specifically shown, in the housing 25. The upper working rolls 27 are independently and vertically movable by electric motors 29 acting through various gearing, not specifically designated, and rods 30; it being apparent that two rods are associated with each roll. The lower and upper sets of working rolls 26 and 27, respectively, are horizontally offset from each other, or staggered so that the working rolls may nest thereby defining a sinuous path of strip travel.

Journalized in the housing 27 at its ends is a transversely extending pinch roll 32 which is adapted to cooperate with a vertically movable pinch roll 33. The pinch roll 33 has its ends journalized in blocks 34 that are rigidly attached to the lower ends of a pair of rods 35 which in turn are connected to the pistons of a pair of fluid cylinders 31 mounted on top of the housing 25. Between the pinch rolls 32 and 33 and the lower and upper working rolls 26 and 27 there are provided strip guides 36 above and below the path of strip travel, which serve to guide the leading end of the coil of strip during initial threading operations. These strip guides in no way interfere with the normal operation of the roller leveller as is readily apparent.

Positioned rearwardly of the pinch rolls 32 and 33 immediately below the path of strip travel and journaled in the housing 25 is a guide roll 37. Suitable angled strip guiding plates 48 are positioned intermediate the guide roll 37 and the pinch rolls 32 and 33 for initially guiding the free end of a coil of strip material.

For driving the working and pinch rolls an electric motor 38 is mounted on the table 24 to one side of the housing 25. The drive shaft of the motor 38 is operatively coupled with a plurality of wobbler shafts 39 for driving these last mentioned rolls via suitable gearing contained in a gear box 40. The driving arrangement is such that the upper working rolls 27 and the upper pinch roll 33 can be adjusted and moved in the vertical direction without breaking the driving connection for these rolls.

As evidenced in the drawing, the housing 25 is provided with an integral and rearwardly extending bracket 44 adjacent the top edge thereof above the path of strip travel. Rigidly mounted from this bracket in depending relation therefrom is a generally I-beam-like member 41 which is considerably elongated, being approximately twice as long as any of the rolls utilized in the roller leveller and extending appreciable distances outwardly

of the housing 25. The bottom portions of the I-beam like member 41 serve as guides for a pair of transversely spaced channel-shaped slides 42 each of which has a restricted opening and carries a depending mounting bracket 43. It will be readily observed that the channel-shaped slides 42 are adapted for transverse sliding movement on the I-beam-like member 41 in transverse relation with respect to the path of strip travel.

Each of the mounting brackets 43 journals a shaft 45, 10 see Figures 6 and 7, which protrudes inwardly—i.e. toward the center of the pass line of the strip—in the manner shown. Keyed to the protruding end portion of the shaft 45 is a finger or wedge 46 having a pointed end portion and a contoured upper surface 47 adapted at 15 certain times and in a manner to be hereinafter more fully described to break the outer end of a coil of metal strip free for initial feeding into the roller leveller. It will be noted that the upper surface 47 of the finger or wedge 46 is arcuately contoured to form a curved surface which, in cooperation with the various rolls and strip guides of the roller leveller, is operative to initially feed the end of the coiled metal strip into the roller leveller.

Mounted on the outward end of each of the mounting 20 brackets 43 is a hydromotor 49 whose output shaft 50 is drivingly coupled with the shaft 45 in such a manner that upon energization of the hydromotor 49 the finger or wedge 46, which is keyed to the shaft 45, is caused to rotate. Hydromotors are well known in the art, comprising in general fluid motors whose output shafts are limited to a predetermined degree of rotative movement. By utilizing such driving devices for rotating the wedges or fingers any movement thereof beyond a predetermined point is prohibited and the wedges or fingers can be maintained in pressure contact with the coil.

As shown in Figure 6 of the drawing, each of the mounting brackets 43 is provided with an outwardly extending web 51 which pivotally receives, by means of a pin 52, a clevis 53 mounted on the piston rod of a fluid cylinder 54. The fluid cylinder 54 is pivotally mounted between a pair of depending plates 55 which form a mounting clevis and are attached to the outer end of the I-beam like member 41. The arrangement is such that upon proper actuation of the fluid cylinders 54 35 the fingers or wedges 46 may be moved transversely toward or away from the path of strip travel.

The apparatus of the present invention also incorporates means for retarding movement of the coils 10 to the coiling station when the same are being readied for uncoiling and further means to engage the outer convolution of the coil whereby when the fingers 46 engage the end of the coil this convolution does not spring in a direction away from the roller leveller. This first mentioned means comprises a bumper cylinder 63 having an adjustable outlet valve which mounts on its piston rod a coil-engaging and pivotally mounted fixture 64. As will be observed in Figure 1 of the drawing, the rear end of the bumper cylinder is pivotally mounted on a support 65 and the arrangement is such that the bumper cylinder 63 forms in effect a shock absorber to take the impact of a coil 10 rolling into the uncoiling station 15 thereby preventing damage to the roller leveller and other appurtenant equipment.

To prevent springing of the outer convolution of the coil in the wrong direction a roller 56, shown in Figure 5 to be hollow and journaled on a shaft 57, but which may be driven by suitable apparatus, not shown, is mounted between a pair of rearwardly directed and downwardly angled arms 58. These arms are pivotally mounted at their forward ends between spaced brackets 59 which are attached to and extend from the top rear edge of the roller leveller. Another arm 69 is rigidly attached to the inner ends of the spaced arms 58 so that the arms 58 and 60, in effect, a bellcrank adapted 70 to move the roller into and out of engagement with a

coil in the uncoiling station. To actuate the bellcrank a clevis-like fitting 61 mounted on the end of the piston rod of a fluid cylinder 62 is attached to the end of the second arm 60.

In operation of the apparatus above described the driving mechanism for the conveyor 11 is energized to move a coil 10 toward the uncoiling station. As the coil moves toward this station the fluid bumper cylinder 63 is actuated in such a manner that the forward movement and momentum of the coil is absorbed as the same rolls into the uncoiling station thereby preventing damage to any of the equipment. As the coil becomes seated on the saddle 17 the cylinder 18 is energized to center the eye of the coil with respect to the heads of the uncoiler. The heads of the uncoiler are then moved toward each other to firmly and tightly grip the coil therebetween and center the same with respect to the processing apparatus.

After the coil is tightly gripped and centered the fluid cylinder 62 is properly energized to bring the roller 56 into pressure engagement with the surface of the coil. At the same time the cylinders 54 are actuated whereby the fingers or wedges 46 are moved to a position directly above and adjacent the side edges of the coil. The positioning of the wedges may be controlled by adjustable stops which limit inward movement of the fingers but yet are adjustable to accommodate coils of different widths. The hydromotors are now actuated to bring the pointed fingers into contact with the coil and it will be observed that the curvature along the bottom edges of these fingers is approximately the same as the curvature of coil to provide ample contact areas with the outer periphery of the coil. The control of the cylinders 54 and hydromotors 49 may be interconnected and arranged so that movement of one of the fingers will require a like movement of the other and that the fingers exert a predetermined pressure on the coil whereby these members will always engage it regardless of irregularities in its shape.

With the coil properly positioned and the fingers in engagement therewith, the uncoiler is energized to rotate the coil and it should be apparent that the sharp pointed portions of the fingers will separate the end of the coil from the coil proper. The roller 56 prevents the freed outer end from "springing" in a direction away from the roller leveller and as the uncoiler continues to rotate the coil the leading end of the strip is forced to ride over the arcuately contoured upper surfaces 47 of the fingers into the previously opened roller leveller. One of the most important aspects of the invention is that the upper surfaces of the fingers, in cooperation with guide roll 37, strip guiding plates 48, pinch rolls 32 and 33, strip guides 36 and the upper and lower sets of working rolls 27 and 26, form a confining or guiding means for the end section of the coil whereby the same cannot become entangled in the apparatus and the threading or initial feeding operation takes place in an automatic manner without stopping the uncoiler. When the end of the strip passes through the roller leveller the coil peeler is no longer needed and the fingers may be retracted to their original positions upon proper actuation of the fluid cylinders 54 and the hydromotors 49, it being observed that this operation also may be carried out without stopping or retarding the passage of strip through the roller leveller and the other machines in the process line. The roller 56 can also be retracted upon proper energization of the fluid cylinder 62 without interfering with the uncoiling operation.

The uncoiling operation then continues at the desired speed until the coil is nearly exhausted since the "hook" on the last convolution of the coil must be straightened. This "hook" is formed at the end of the strip by the apparatus originally winding the coil and it is usually undesirable to have this "hook" pass through the process equipment without at least some straightening. The guide roll 37 not only serves to guide the strip but also acts as

a catch for the hook end of the coil thereby absorbing the shock of the same and, to some extent, straightening the same. After the coil is finally payed out the uncoiling station is again opened and another coil is moved into position and started through the processing line in the manner explained above.

It should thus be apparent that we have accomplished the objects initially set forth by providing an improved coil peeler of a type well adapted for utilization in a continuous process line. The steps of breaking the end portion of the strip from the coil and initially feeding the same through the processing machines may be carried out under the control of a single operator in a minimum of time.

15 Although we have shown and described a specific illustrated embodiment of the invention, it should be understood many changes may be made therein without departing from the invention and that reference to the following appended claims should be had in determining the 20 true scope of the invention.

We claim:

1. A coil peeler comprising a generally pointed finger, means mounting said finger in vertically disposed relation with respect to a coil to be unwound and the path of 25 strip travel, driving means operatively coupled with said finger for moving said finger transversely with respect to and into and from the projected vertical plane of the path of strip travel, power means operatively connected with said finger for moving said finger into engagement 30 with a coil to be unwound when said finger is within the projected vertical plane of the path of strip travel, said mounting means comprising a bracket, a shaft journaled in said bracket, said finger being rigidly mounted on said shaft, said power means having an output shaft and 35 being mounted on said bracket, and said output shaft being axially aligned and operatively coupled with said first mentioned shaft whereby upon energization of said power means said finger is caused to rotate.

2. Apparatus according to claim 1 further characterized in that said mounting means comprises an elongated and transversely extending member, a slide slidably mounted on said transversely extending member, said bracket being mounted from said slide, said driving means being drivingly connected to said bracket for moving 45 said slide on said transversely extending member, said driving means comprising a fluid cylinder having a piston rod, said cylinder mounted from one outer end of said transversely extending member, and said piston rod of said cylinder being connected to said bracket.

3. Apparatus of the character described comprising a 50 pair of pointed coil-engaging fingers, means mounting said fingers in vertically disposed relation with respect to a coil to be unwound and the path of strip travel, said mounting means comprising an elongated and transversely disposed member extending across and beyond the path 55 of strip travel, a pair of slides mounted for sliding movement on said transversely disposed member, each of said slides journaling a shaft therein, each of said fingers being rigidly attached one to each of said shafts, a driving motor mounted on each of said slides, said driving 60 motors having their output shafts drivingly coupled with said shafts journalled by said slides, and driving means mounted from said transversely disposed member adjacent each end thereof for said slides for moving the 65 same along said transversely disposed member.

4. A strip processing machine of the type having means 70 for processing metal strip passing therethrough and means to separate the outer end section of metal strip from a coil thereof, said means to separate comprising a coil-engaging finger mounted from said machine rearwardly of said means for processing, means to move said finger in a generally vertical direction into and out of contact with a coil, said finger having a pointed end portion and an arcuately contoured coil-engaging surface, the other major surface area of said finger being arcuately con-

7
toured and forming guiding means for guiding the loosened outer end section of a coil into said means for processing, means mounting said coil-engaging finger for transverse movement into and from a position outwardly of the path of strip travel to a position within the vertical projection of the path of strip travel, said guiding means further comprising a transversely extending guide roll journaled for rotation in said machine directly in front of said coil-engaging finger, said other major surface area of said coil-engaging finger and the peripheral surface of said guide roll forming a continuous guiding surface when said finger is within the vertical projection of the path of strip travel, and said guide roll being operative to snag the hooked end portion of the coil of metal strip when said finger is retracted into said position outwardly.

5. An uncoiling station of the type adapted to receive a coil, thread the end thereof to a processing machine and then to pay-off the metal strip comprising a coil saddle adjacent said processing machine, means to move coils into said coil saddle, means for rotatably supporting the coils, means to initially break the outer convolution of a coil therefrom when the same is supported by said rotatably supporting means, said means to initially break comprising a wedge shape coil-engaging finger,

6
means to prevent springing of said outer convolution in the wrong direction when the same is broken from the coil, said means to prevent springing comprising a vertically movable roller supported above said coil saddle and said rotatably supporting means to the rear of said coil-engaging finger, said coil-engaging finger being mounted from the rear of a strip processing machine, linkage means supporting said vertically movable roller from said processing machine in overhanging relation 10 with respect to said coil saddle, and power means on said processing machine for moving said vertically movable roller.
